(57) **CLAIM**

The ornamental design for a plant pot, as shown and described.

DESCRIPTION

FIG. 1 is a perspective view of a plant pot showing our new design;

FIG. 2 is a front elevational view thereof, the back elevational view being a mirror image of the front view;

FIG. 3 is a right side view thereof, the left side elevational view being a mirror image of the right side view;

FIG. 4 is a top plan view thereof; and,

FIG. 5 is a bottom plan view thereof.

The broken lines are included for the purpose of showing portions of the plant pot that form no part of the claimed design.

1 Claim, 3 Drawing Sheets(56)
